DESIGN FOR A LIGHTING FIXTURE

Edward F. Sibbert, Brooklyn, N. Y., assignor to
S. H. Kress and Company, New York, N. Y., a
corporation of New York

Application February 23, 1937, Serial No. 67,796

Term of patent 14 years

To all whom it may concern:

Be it known that I, Edward F. Sibbert, a citizen of the United States and residing at Brooklyn, New York, have invented a new, original, and ornamental Design for a Lighting Fixture, of which the following is a specification, reference being had to the accompanying drawing, forming part thereof, and in which:

Fig. 1 is a bottom plan view of a lighting fixture showing my new design; and

Fig. 2 is a perspective view thereof.

The essential features of my invention are shown in full lines and reside in a baffle unit having concentric walls generally downwardly extending, of length progressively greater from the periphery toward the center of the unit, said walls being connected by generally radial pairs of walls which simulate petals.

I claim:

The ornamental design for a lighting fixture, as shown and described.

EDWARD F. SIBBERT.
